COMBINED LETTER SCALE, CALENDAR AND PAPER HOLDER

Henry Ruskin, 21 Nomahagan Court, Cranford, N.J.

Filed Apr. 30, 1963, Ser. No. 74,669

Term of patent 14 years

(Cl. D52—10)

FIG. 1

FIG. 2

FIG. 3FIG. 4

The essential features of my design reside in the portions shown in solid lines.

I claim:

The ornamental design for a combined letter scale, calendar and paper holder, substantially as shown and described.
